WITNESS:

ATTORNEY

UNITED STATES PATENT OFFICE.

CHARLES FRANKLIN THOMPSON, OF GREENSBORO, NORTH CAROLINA.

RAIL BRACE.

Application filed November 26, 1921. Serial No. 517,984.

To all whom it may concern:

Be it known that I, CHARLES FRANKLIN THOMPSON, a citizen of the United States, residing at Greensboro, in the county of 5 Guilford and State of North Carolina, have invented new and useful Improvements in Rail Braces, of which the following is a specification.

This invention relates to rail braces for 10 railroad rail and has for its object to provide a novel form of brace adjustably positioned between the rail tread and the tie plate, being arranged at an incline therebetween. A further object is the provision 15 of novel means for bracing the rail and preventing it from giving outwardly when a heavy train passes around a curve.

With the above and other objects and advantages in view, the invention consists in 20 the details of construction to be hereinafter more fully described and claimed, and illustrated in the accompanying drawings in which,

Figure 1 is a side elevation of a portion 25 of a rail with the improved brace applied.

Figure 2 is a cross-sectional view through my improved rail and showing the bracing means.

Figure 3 is a plan view of the base plate. 30 Referring more particularly to the drawings the letter A designates an ordinary railroad rail secured upon the usual cross-ties V.

The rail might be spiked upon the cross-ties in the ordinary manner but I preferably make use of an elongated steel plate 16 which is of considerably greater width than the base portion 10 and which is provided with holes 17 through which are inserted 35 spikes C by means of which the plate is secured to the cross-ties. It is to be observed that the holes 17 are in such position that when the spikes are driven therethrough in the ties the spikes will operate 40 to engage and hold the base 10 of the improved rail.

It is very desirable to provide bracing means for the outer side of the rails at curves and in order to accomplish this I provide the plates 16 with sockets 18 engaged by the ends of rods 19 which carry frames 20, into which are screwed brace members 21 which engage against the lower edges of the ball portions of the rails at the outer portions thereof as clearly shown. 50 This brace structure is of a turn-buckle like construction and it is apparent that the frame 20 may be rotated whereby to tighten the brace 21 against the rail so as to prevent any giving away of the rails in the 55 event of heavy strain.

It is believed that the above description when taken in connection with the accompanying drawings will render the construction and use sufficiently clear so that further 60 explanation is entirely unnecessary.

While I have shown and described the preferred embodiment of my invention, it is of course to be understood that I reserve the right to make such changes in the form, 70 construction and arrangement of parts as will not depart from the spirit of the invention or the scope of the subjoined claim.

Having thus described my invention I 75 claim:

In a device of the character described, a rail, a tie plate supporting the rail and presenting a socket laterally of the rail, a brace rod having one end loosely engaged in the 80 said socket and presenting a frame at its other end having a threaded bore, and a brace member having one end screwed into the said threaded bore and having the other end adapted to engage the tread of the rail, 85 said brace rod and member extending at an incline between the said rail tread and the tie plate.

In testimony whereof I affix my signature.

CHARLES FRANKLIN THOMPSON.
